Primary Examiner — Sandra S Snapp*Assistant Examiner* — Mehri F Bajoul*(74) Attorney, Agent, or Firm* — Leong C. Lei(57) CLAIM

The ornamental design for a soccer table, as shown and described.

DESCRIPTION

FIG. 1 is a perspective view of a soccer table showing my present design;

FIG. 2 is a front view thereof;

FIG. 3 is a rear view thereof;

FIG. 4 is a left side view thereof;

FIG. 5 is a right side view thereof; and,

FIG. 6 is a top view thereof.

All the broken lines in the drawings, including the nets, depict portions of the soccer table and form no part of the claimed design.
